UNITED STATES PATENT OFFICE.

RUBIN ROSENTHAL, OF BROOKLYN, NEW YORK.

RING AND PLATE THEREFOR.

1,417,352.

Specification of Letters Patent. Patented May 23, 1922.

Application filed January 29, 1921. Serial No. 440,955.

To all whom it may concern:

Be it known that I, RUBIN ROSENTHAL, a citizen of the United States, and a resident of the city of New York, borough of Brooklyn, in the county of Kings and State of New York, have invented a new and Improved Ring and Plate Therefor, of which the following is a full, clear, and exact description.

This invention relates to jewelry and particularly to an arrangement of ring and ornamental plate forming a back ground for an ornament associated therewith and has for an object to provide an improved construction and arrangement of the ring and plate whereby the plate may be readily removed without injury thereto or to the ring and a differently ornamented backing substituted.

Another object in view is to provide a ring with a depression for receiving an enameled plate and ornament, the entire arrangement being so constructed as to properly fit together and present a stud adapted to be secured to the ring body in a manner to be readily removed so that a different ornament may be supplied without injuring the enamel.

In the accompanying drawing—

Figure 1 is a top plan view of the ring and plate embodying the invention.

Figure 2 is a section through Figure 1 on line 2—2.

Figure 3 is a perspective view of the plate shown in Figure 1.

Referring to the accompanying drawing by numeral, 1 indicates the ring body which is provided with an enlargement 2 in which is formed a recess or seat 3 adapted to receive the thin plate 4. This plate is provided with a coating of enamel 5 on one face though if desired some other material could be used as coating. This plate forms a back ground and is provided with an aperture 6 through which the stem 7 projects, said stem being preferably a part of the ornament 8 adapted to fit flatwise against the enamel 5. The stem 7 may be held in place by riveting as shown in Figure 2. Preferably, riveting is used as too much heat would injure the enamel 5.

The enameled plate owing to its size and

thickness, being very thin and the enameling being inexpensive, the plates can be made very cheap and kept in stock in differently colored enamel.

In case someone should desire to purchase the ring as shown in Figure 1 but should desire some other emblem or other ornamentation the jeweler could readily force the stem 7 out of the position shown in Figure 2 and consequently, remove the ornament 8 and plate 4 without injuring the emblem or enameled plate or both or the enamel 5. A new ornament could be provided and fastened in place without injury to the enamel 5.

Heretofore, it has been necessary to secure the ornament in place by soldering or by some other means and destroy the enamel 5. New enamel must be applied and baked before the job has been completed. This takes a comparatively long time and is expensive whereas by providing a removable ornament and a removable plate a new ornament may be supplied at any time without injury to the ornament or to the plate and also a plate having a different colored enamel may be supplied.

When it is desired to remove applicant's emblem, the upset or riveted part of the stem 7 is cut away, or if desired, the stem may be bodily pushed through the opening in the ring. As the parts are very small this may be done especially as the gold is comparatively soft. The ornament 8 is pressing against the enamel but is not secured thereto so that as soon as the stem 7 has been released the ornament will easily move with the stem.

What I claim is:—

A ring of the character described, comprising a body having a recess in its face and an opening in the center of the bottom of the recess, a thin metallic plate coated on one face with enamel and having a central opening, said plate removably fitting in the recess and the body, and an ornament fitting on the enamel plate and having a stem projecting through the openings of the plate and the body and riveted on the inner face of said body.

RUBIN ROSENTHAL.
